DESIGN FOR A PICTURE FRAME

Sara Colef, Benton Harbor, Mich., assignor to Benton Glass Company, Benton Harbor, Mich.,
a corporation of Michigan

Application July 23, 1945, Serial No. 120,891

Term of patent 7 years

(Cl. D29—20)

To all whom it may concern:

Be it known that I, Sara Colef, a citizen of the United States, residing at Benton Harbor, in the county of Berrien and State of Michigan, have invented a new, original, and ornamental Design for a Picture Frame, of which the following is a specification, reference being had to the accompanying drawing, forming part thereof, in which:

Fig. 1 is a front view slightly in perspective of a picture frame, showing my new design,
Fig. 2 is a side elevation, and
Fig. 3 is a sectional view on line 3—3 of Fig. 1.

I claim:

The ornamental design for a picture frame, as shown,

SARA COLEF.
